(57) **CLAIM**

The ornamental design for antitheft device for cameras, as shown and described.

DESCRIPTION

FIG. 1 is a perspective view of an antitheft device for cameras showing my new design;

FIG. 2 is a further perspective view thereof;

FIG. 3 is a front view thereof;

FIG. 4 is a rear view thereof;

FIG. 5 is a left side view thereof;

FIG. 6 is a right side view thereof;

FIG. 7 is a top plane view thereof;

FIG. 8 is a bottom view thereof;

FIG. 9 is a cross-sectional view taken along line 9-9 in FIG. 7; and,

FIG. 10 is a reference view of the antitheft device for cameras in use.

The broken lines shown in the drawings depict environmental subject matter that form no part of the claimed design.
